Patented Apr. 15, 1919.

UNITED STATES PATENT OFFICE.

THOMAS W. FLOWERS, OF GOLDSBORO, NORTH CAROLINA, ASSIGNOR TO E. A. HUMPHREY, TRUSTEE, OF GOLDSBORO, NORTH CAROLINA.

ADJUSTABLE SHADE-ROLLER HANGER.

1,300,366.

Specification of Letters Patent. Patented Apr. 15, 1919.

Application filed January 11, 1919. Serial No. 270,681.

To all whom it may concern:

Be it known that I, THOMAS W. FLOWERS, a citizen of the United States, and a resident of Goldsboro, in the county of Wayne and State of North Carolina, have invented certain new and useful Improvements in Adjustable Shade-Roller Hangers, of which the following is a specification.

My invention relates to improvements in adjustable window shade hangers, and it consists in the constructions, combinations and arrangements herein described and claimed.

An object of my invention is to provide a hanger for shade-rollers, that can be adjusted to fit any size of shade-roller or window casing, one of the important features of the hanger consisting in the novel construction of the roller brackets at the ends of the hanger.

Other objects and advantages will appear in the following specification, reference being had to the accompanying drawing in which:—

25 Figure 1 is an elevation of a part of a window casing showing the invention applied.

Fig. 2 is a perspective view of the improved hanger,

30 Fig. 3 is a detail view of the combined bar clamp and hanger cord attachment, and

Fig. 4 is a detail perspective view of one end of the hanger, illustrating the improved roller bracket.

35 The improved hanger comprises a pair of extensible bars 1 and 2 that are loosely held together by bands 3 which are secured at 4 to the respective ones of the bars. A combined bar clamp and hanger cord attachment

40 5 has a ring 6 which when pressed downwardly tightens the clamp on the bars and secures whatever adjustment was previously made.

The tubular head 7 of the clamp has a hole 45 into which the end of the hanger cord 8 is inserted. The end of the cord is knotted or provided with some other suitable device to keep it in place in the head. The cord 8 passes over a roller 9 with an eccentric 50 groove, the operation of the roller being to hold the hanger with the shade 10 in any desired position with respect to the window casing.

Caps 11 bind the prongs 12 of the roller brackets 13, in the angularly positioned 55 grooves 14 in the outer ends of the respective bars. Each cap has flanges 11^a that in turn fit in grooves 15 in the sides of each bar, thus not only serving to hold the caps on more securely, but preventing them from 60 slipping off of the ends. The brackets 13 are retained rather more securely by bending the upper ends of the prongs 14 over at 14^a, thus obtaining a hold on top of the bar.

The purpose of the invention is easily understood. The bars 1 and 2 can be extended to any ordinary width of shade roller or window casing. The entire fixture is lowered as much as desired so that the window can be opened to admit fresh air. By means 65 of the arrangement of the end caps and the disposition of the prongs 14, the roller brackets when once put in place are held there permanently. It is only necessary to move the clamp 5 into a central position 70 where the hanger will balance, after each adjustment.

I claim:—

1. A shade-roller hanger, comprising a pair of extensible bars with angularly positioned 80 grooves in the extreme ends, bands encircling the bars to hold them together, said bands being secured to the respective bars, a combined clamp and hanger cord attachment, consisting of a clamp portion encompassing the bars, with a movable clamp ring operating above said portion; shade roller hangers including prongs occupying 85 the aforesaid grooves, with inwardly turned ends resting on top of the bars to prevent the 90 hangers from pulling out, and means including end caps arranged to be secured over said prongs.

2. In a shade-roller hanger, a bar having a pair of grooves disposed transversely 95 thereof near the end and a second pair of grooves disposed at an angle to the first pair, a roller bracket having prongs located in the angular pair of grooves and provided with inwardly bent portions to rest on top of the 100 bar, and a cap slidably fitted over the end of the bar to house the prongs and being provided with flanges to fit in the transverse grooves and keep the cap from coming off.

THOMAS W. FLOWERS.
